FIG. 17

FIG. 18

FIG. 19

FIG. 20

FIG. 1 is a perspective view of a hanger bar for suspending a plate-type electrode showing my new design, broken away to indicate indeterminate length.

FIG. 2 is an end view of the hanger bar shown in FIG. 1. The view from the opposite end is identical.

FIG. 3 is a side view of the hanger bar shown in FIG. 1. The view from the opposite side is identical.

FIG. 4 is a plan view of the hanger bar shown in FIG. 1.

FIG. 5 is an inverted plan view of the hanger bar shown in FIG. 1.

FIG. 6 is a perspective view showing a variation of the hanger bar in FIG. 1, broken away to indicate indeterminate length.

FIG. 7 is an end view of the hanger bar shown in FIG. 6. The view from the opposite end is identical.

FIG. 8 is a side view of the hanger bar shown in FIG. 6. The view from the opposite side is identical.

FIG. 9 is a plan view of the hanger bar shown in FIG. 6.

FIG. 10 is an inverted plan view of the hanger bar shown in FIG. 6.

FIG. 11 is a perspective view of a further variation of the hanger bar shown in FIG. 1, broken away to indicate indeterminate length.

FIG. 12 is an end view of the hanger bar shown in FIG. 11. The view from the opposite end is identical.

FIG. 13 is a side view of the hanger bar shown in FIG. 11. The view from the opposite side is identical.

FIG. 14 is a plan view of the hanger bar shown in FIG. 11.

FIG. 15 is an inverted plan view of the hanger bar shown in FIG. 11.

FIG. 16 is a perspective view of a still further variation of the hanger bar shown in FIG. 1, broken away to indicate indeterminate length.

FIG. 17 is an end view of the hanger bar shown in FIG. 16. The view from the opposite end is identical.

FIG. 18 is a side view of the hanger bar shown in FIG. 16. The view from the opposite side is identical.

FIG. 19 is a plan view of the hanger bar shown in FIG. 16.

FIG. 20 is an inverted plan view of the hanger bar shown in FIG. 16.

I claim:

The ornamental design for a hanger bar for suspending a plate-type electrode, as shown and described.
